UNITED STATES PATENT OFFICE.

JOHN Y. PARKE, OF PHILADELPHIA, PENNSYLVANIA.

GAS-BURNER.

No. 908,607.

Specification of Letters Patent.

Patented Jan. 5, 1909.

Application filed December 5, 1904. Serial No. 235,483.

To all whom it may concern:

Be it known that I, JOHN Y. PARKE, a citizen of the United States, and a resident of the city of Philadelphia, State of Pennsylvania, have invented certain new and useful Improvements in Gas-Burners, of which the following is a full, clear, and complete disclosure.

The object of my invention is to provide such a construction in valves for gas burners and other conduits where a gas or fluid is conveyed from one place to another, that said valve will be simple and inexpensive to manufacture, efficient in operation and very durable in wearing qualities.

Briefly, my invention comprises a fluid conduit, within which is located a loose valve member which is adapted to be unseated when a suitable key is turned to allow the passage of the gas or other fluid, said valve member being preferably held in position by means of a spring member.

For a full, clear and exact description of one embodiment of my improvements reference may be had to the following specification and to the accompanying drawing forming a part thereof, in which—

Figure 1 is a side elevation partly in section of one embodiment of my improved valve; Fig. 2 is a similar enlarged view thereof also showing certain parts thereof in section; and Fig. 3 is a detail view of the key, showing the cam for operating the valve.

Referring to the drawing the numeral 1 indicates a casing of a gas jet or other fluid conduit and 2 a key for operating my improved valve, said key rotatably mounted in the casing 1 in any suitable manner. The passage 3 within the casing 1 is expanded into an enlarged chamber 4 the corner between the said passage and chamber being beveled as indicated at 5 to form a valve-seat. Upon this valve-seat is placed a spherical body or ball 6, accurately shaped, and preferably of steel or other durable material. A plunger or follower 7 is adapted to rest upon said ball 6 and is yieldably held in position by means of a coiled spring 8, said coiled spring being held within the chamber 4 in any suitable manner as in this instance by abutting against the lower end of the lava tip 9. It is obvious that the plunger 7 may be omitted and the spring 8 bear directly on the ball, but I

prefer to use the plunger inasmuch as the end thereof gives a surface having a sliding contact with the ball. As means for displacing said ball or valve member 6 from its seat I provide a pin 10 which passes through an opening 11 in the casing 1, the inner end of which is adapted to engage the ball 6. The outer end of said pin 10 is adapted to engage with a suitable cam 12 in the form of an inclined surface or groove carried by the key 2.

In operation it will be seen that when the key 2 is rotated upon its axis the cam 12 will force the pin 10 inward and thereby displace the ball 6 against the yielding pressure of the plunger 7 which will allow sufficient space between the valve-seat 5 and the ball 6 to permit the gas or other fluid to easily pass. When the key is rotated in the opposite direction from that just described the ball 6 will be reseated on the valve-seat and the passage 3 closed.

My improved form of valve forms a fixture or burner for gas jets which is especially adapted to gases which give out a great amount of heat, such as acetylene.

Having thus described my invention it is obvious that changes may be made in the form, proportion and arrangement of parts and mechanical equivalents may be substituted without departing from the spirit and scope of my invention, but

What I claim and desire to protect by Letters Patent of the United States is:—

1. A fluid supply conduit comprising a casing provided with a straight passage for fluid, having one portion of larger bore than the remaining portion, a valve seat at the junction of the said portions, a ball of larger diameter than the bore of the smaller portion of the said passage, loosely seated in the valve seat, a rod slidably mounted near the part of the casing surrounding the passage of larger bore, and a key rotatably mounted on the casing and provided with a flange substantially at right angles to the said rod and having a cam surface which engages the outer end of the rod for reciprocating the said rod. 90 95 100

2. A fluid supply conduit comprising a casing provided with a straight passage for fluid, having one portion of larger bore than the remaining portion, a valve seat at the junction of the said portions, a ball of larger diameter than the bore of the smaller por- 105 110

tion of the said passage, loosely seated on the valve seat, a spring located in the larger portion of the said passage, and holding the ball against the valve seat, a rod slidably mounted in the part of the casing surrounding the passage of larger bore, and a key rotatably mounted on the casing and provided with a flange substantially at right angles to the said rod and having a cam

surface which engages the outer end of the 10 rod for reciprocating the said rod.

In witness whereof, I have hereunto set my hand this 21st day of November, A. D. 1904.

JOHN Y. PARKE.
